CLAIM

The ornamental design for the electric liquid vaporizer, as shown.

DESCRIPTION

FIG. 1 is a perspective view of an electric liquid vaporizer showing our new design;

FIG. 2 is a rear view of the electric liquid vaporizer of FIG. 1;

FIG. 3 is a right side elevational view of the electric liquid vaporizer of FIG. 1;

FIG. 4 is a left side elevational view of the electric liquid vaporizer of FIG. 1;

FIG. 5 is a perspective view of the housing unit of FIG. 1;

FIG. 6 is a right side elevational view of the housing unit of FIG. 1;

FIG. 7 is a left side elevational view of the housing unit of FIG. 1;

FIG. 8 is a bottom plan view of the housing unit of FIG. 1;

FIG. 9 is a cut-away front view of the housing unit of FIG. 1;

FIG. 10 is a perspective view of an alternate embodiment electric liquid vaporizer; and,

FIG. 11 is a right side elevational view of the electric liquid vaporizer of FIG. 10.
